CONTAINER OPENER

Leigh R. B. Atwater, Boston, and Edward C. Donnelly, Jr., Dover, Mass., assignors, by mesne assignments, to said Donnelly, Jr.

Application January 21, 1953, Serial No. 332,204

1 Claim. (Cl. 30—6.1)

This invention relates to a container opener and pertains more specifically to a can opener adapted to form a plurality of openings in the end wall of a can in a single operation.

One object of the invention is to provide an opener for liquid containers made of sheet metal, which opener is adapted to form in one stroke at least two openings in the container wall, one of the openings serving as a discharge opening for the liquid, the second opening serving as an air inlet.

Another object is to provide a can opener of the shear type which fulcrums about the periphery of an end wall of the can to form at least two openings in the end wall of the can in a single stroke.

Another object is to provide a shear-type can opener which forms a large liquid discharge opening adjacent the margin of an end wall and a smaller air inlet opening nearer the center of the end wall in a single operation.

Still a further object is to provide a shear-type can opener capable of forming a plurality of openings in the end wall of a can in a single stroke, the length of the stroke and hence the size of the openings being limited by abutment of the handle portion of the can opener against the rim of the can.

Still another object is to provide an integral one-piece can opener of the type described which may readily and economically be formed from metal plate.

Other and further objects will be apparent from the drawings and the description which follows.

In the drawings,

Fig. 1 is a view in perspective partly broken away and in section of the opener of the present invention;

Fig. 2 is a view in elevation partly broken away and in section of a portion of the opener in position on the end of a can preparatory to openings;

Fig. 3 is a view in elevation partly broken away and in section showing the opener on the can at the completion of the opening stroke;

Fig. 4 is a plan view of the end of the can showing the openings formed by the opener; and

Fig. 5 is a view in elevation showing the opener of the present invention in position for use as a bottle cap remover.

Referring to the drawings, the container opener of the present invention is preferably formed as by die-stamping or punching from a single metal plate to provide an elongated rigid handle portion 10 which is bent back sharply upon itself at one end, as at 11. The bent-back portion 12 then extends rearwardly away from the axis of the handle portion at an angle somewhat less than 90° to form a generally arcuate triangular can-piercing and shearing blade 13. The two converging edges 14, 14 of this blade are sharpened to serve as cutting edges and meet at a pointed tip 15.

A hooked lug 20 is struck from the handle portion adjacent bend 11, this lug being provided with a slight hook 21 at its tip which is adapted to engage the peripheral

seam or bead 22 around the margin of the can, as shown in Fig. 2. Lug 20 and piercing element 13 extend in the same general direction from the handle, but the lug 20 is much shorter than the piercing element 13. The space between lug 20 and piercing element 13 is somewhat greater than the width of the usual rolled seam on the end of a can, as shown in Fig. 2, in order to facilitate placing the opener in position.

A second generally triangular can-piercing element 25 is struck from the handle portion at a point spaced from lug 20 by a distance preferably somewhat greater than the radius of the can on which the opener is to be used. Element 25 likewise is provided with a pair of convergent cutting edges 26, 26 terminating in a pointed tip 27. The size of element 25 is such that its tip lies much closer to the axis of the handle portion than the tip of element 13.

In order that the opener may serve a dual function and operate as a bottle cap remover, a part 30 of the handle portion may be offset, as by bending, and a second hooked lug 31 may be struck from the handle portion adjacent the offset part.

In use, the opener is placed in the position shown in Fig. 2 with hooked lug 20 engaging the rolled seam at one end of the can with the handle portion extending upwardly and inwardly toward the axis of the can. The handle portion is then rocked downwardly to the position shown in Fig. 3, the device pivoting about lug 20 as a fulcrum. During this rocking stroke the pointed tip of piercing element 13 first punctures the end wall of the can followed by a shearing of the end wall along divergent lines of the cutting edges 14 to provide a relatively large triangular opening 35. When the formation of this opening is almost completed, the pointed tip 27 of the second piercing element 25 pierces the end wall at a point somewhat beyond the center, as shown in Fig. 4, and the cutting edges 26, 26 of this element then shear a small triangular opening 36 in the end wall. At this point, the handle portion 10 abuts against the rim of the can opposite the portion engaged by lug 20 and prevents further rocking of the implement. Accordingly, the size of the two openings 35 and 36 is positively controlled.

We have found that for optimum results the area or size of opening 35, which serves as the liquid discharge openings, should be from 11 to 12 times the area of air inlet openings 36. For the usual 12-ounce container, opening 35 is preferably in the shape of an isosceles triangle, with its base and altitude both approximately $\frac{3}{4}$ of an inch long to give an opening which is from 0.5 to 0.6 square inch in area. With an opening of these dimensions, a 12-ounce container filled with a liquid having a viscosity approximately equal to that of water can be emptied in $2\frac{1}{2}$ to 3 seconds without excessive turbulence and with a smooth, even flow. For best results it has been found that the air inlet opening should be located beyond the center of the can end, as viewed from opening 35. Preferably it is located closer to the center of the can end than to the margin in order to minimize the force required to push the piercing element 25 through the sheet metal. When the size of this inlet opening is reduced below $\frac{1}{12}$ that of the liquid discharge opening, the rate of discharge is greatly reduced and the turbulence is greatly increased. When the size of the air inlet opening is greater than about $\frac{1}{11}$ of the size of the liquid discharge opening, the liquids tend to emerge from both openings simultaneously.

In using the implement of the present invention as a bottle cap remover, it is merely turned over, as shown in Fig. 5, and the lug 31 is engaged under the edge of bottle cap 38, whereupon an upward rocking movement of the handle portion suffices to remove the cap.

The opener of the present invention may conveniently

be made in a variety of sizes, each being particularly adapted for use with a can or container of specific size, although a single size implement will perform quite well on containers which vary considerably in size.

Although we have herein described specific embodiments of our invention we do not intend to limit ourselves solely thereto but to include all of the obvious variations and modifications within the spirit and scope of the appended claim.

We claim:

A unitary can opener formed from a single metal plate comprising an elongated handle portion having an end bent back sharply terminating in a generally arcuate triangular can-piercing element having a pair of converging cutting edges with a pointed tip, said element extending generally outwardly and rearwardly from said handle portion, a hooked lug struck from said handle portion adjacent the bend thereof extending generally in the same direction as said can-piercing element but terminating closer to the plane of the handle and adapted to en- 20

gage the peripheral seam of the can when said handle portion is rocked thereabout to force the can-piercing element through the end wall of the can near its margin, and a second generally triangular can-piercing element struck from the handle portion at a point more remote from said hooked lug than the first said element and extending in the same general direction as the first said element, said second element having a pair of converging cutting edges ending in a pointed tip which is disposed closer to the axis of the handle than the tip of the first said element so that it penetrates the end wall of the can subsequent to the first element to form a smaller opening near the center of the can end.
